UNITED STATES PATENT OFFICE.

HARRY A. MUSHAM, OF CHICAGO, ILLINOIS.

MILITARY PROTRACTOR.

Refiled for abandoned application Serial No. 74,336, filed December 9, 1925. This application filed August 29, 1927. Serial No. 216,184.

This invention relates to an improved measuring instrument, and it has more particular reference to a military protractor for use in military science in reading maps, laying out and measuring angles, and laying off angles for the degree and mil system of circular measurements.

The present application is a substitute for an application identified by Serial No. 10 74,336, filed by me under date of December 9, 1925, now abandoned.

Briefly described, the alleged novelty herein embodied is based upon an instrument of this class which comprises a rectangular sheet of appropriate material formed with a slot which runs parallel to one longitudinal edge, this slot constituting the base line of a protractor and being formed with a centrally located vertex. 15 Also located on the sheet and disposed in spaced parallelism to the first named slot is a second longitudinal slot. Cooperating with these two longitudinal slots, we find a pair of relatively short vertical end slots 20 whose opposite ends extend beyond and thereby overlap the end portions of the first named slots. The opposite edges of the second named longitudinal slot and the end slots are formed with individual scale lines 25 radiating from the vertex and arranged on the overlapping end portions of the end slots in such a manner as to provide for continuity of measurement.

In the drawing:—

35 The single figure represents a top plan view of an instrument constructed in accordance with the present invention.

Referring now to the drawings by reference numerals it will be observed that the reference character 1 designates generally a rectangular piece of material which may be of metal, ivory, celluloid, rubber, or any appropriate material. Disposed within the area of this sheet and spaced from the marginal edges we find the four individual slots 40 briefly referred to. For example the reference character 2 designates one of the vertical or end slots, 4 designates a similar end slot at the opposite end of the sheet and 3 a horizontal slot located between the two end slots, being disposed somewhat close to the top edge of the sheet. Disposed in spaced parallelism with the slot 4 is a bottom slot 5 having a vertex 8 formed centrally on the inner edge thereof. Along the

inner edges of slots 2, 3, and 4 is placed a scale of degrees represented by the reference numeral 8. This scale runs from 0 degrees on the right to 180 degrees on the left. Also it runs from 180 degrees on the right to 360 degrees on the left. Along the outer edges of slots 2, 3 and 4 is placed a scale of angular measurement in mils, designated by the reference characters 7 and starting from 0 mils from the right and continuing to 3200 mils on the left, and from 6400 mils on the left to 3200 mils on the right.

At this point attention is invited to the fact that the scales for angular measurement used in military terms are made on two systems. First, the degree system where system is divided into 360 degrees, each degree being divided into 60 minutes, and each minute being divided into 60 seconds. Secondly, 70 there is the mil system where the circumference is divided into 6400 equal parts called mils. A mil is the angle subtended by an arc of one foot at a distance of 1000 feet. Incidentally the figure 6400 is a practical figure adopted by the army instead of 6283.2, the actual number of mils in a circumference. 75

As before stated the particular advantage of this arrangement of individual scales is to provide for continuity of measurements so that there will be no break in the scale. Hence the overlap is sufficient to provide for the scales of degrees of mils being continuous to this extent. For instance, the 30 degree graduation is found in the inner edge of slot 2 and on the inner edge of slot 3 also. In reading or laying off angles the user starts at 0 degrees or 0 mils as the case may be from the right, reads up the scales on the slot 2 as far as they go, then locates the slot 90 2 and slot 3, reads along slot 3 and down on slot 4, locating as before the last reading of slot 3 on slot 4. It is thus seen that continuity of angular measurement is provided. Of course the widths of slots 2, 3, 4 and 5 is 95 not definitely specified but will be such as to make for convenient use of the scale and marking of the pencil on either edge of the slots.

Attention is also invited to the fact that the 105 slots so overlap at their upper and outer ends that it is possible to make the scale continuous as for instance at 30 degrees. For example, up to 30 degrees the right hand slot 4 is used, from 30 degrees to 150 degrees the 110

horizontal slot 3 is used, from 150 degrees to 180 degrees the left hand slot is used for measuring and plotting angles in degrees. If the angles are desired in mils then the mils scales are used. This placing of the mils of angular measurement around an arrangement of slots permits placing of more than one direct reading and sliding the scale of angular measurement on a protractor. The 10 ordinary protractor can only have one scale of angular measurement that can be used directly for reading and plotting the scale of angular measurement on a protractor. By direct reading is meant, reading the angle by 15 means of a scale, the division points of which can be marked with a pencil or a pointer. More than one scale can be placed on the ordinary protractor, but not direct reading. If more than one scale is used, then one 20 might be fitted inside the edges, division points cannot be marked by pencil.

By arranging the scales herein shown in spaced relation to the marginal edges of the sheet, sufficient space is left for disposition 25 of coordinate rules. For example, a coordinate ruler for a grid interval of 1000 yards and a map scale of 1 to 20,000 is shown at 13 merely to illustrate this feature of the invention.

30 From the foregoing description and drawing it will be seen that I have produced an exceptionally original measuring instrument for military purposes which is characterized by the presence of cooperating overlapping 35 slots having individual scale measurements

on their opposite edges so located as to provide for continuous measurements for reading maps and laying out at measuring angles according to systems of angular measurements.

40 Persons familiar with instruments of this general class will be able to obtain a clear understanding of the alleged novelty, therefore a more lengthy description is believed unnecessary.

45 Minor changes in the shape, size, and rearrangement of features may be resorted to within the scope of the adjoined claim.

Having thus described the invention, what I claim as new is:—

50 A measuring device of the class described comprising a rectangular sheet formed with a slot running parallel to one longitudinal edge and having its inner edge forming the base line of a protractor, said inner edge having marked thereon a vertex, a second longitudinal slot, and a pair of transverse slots, spaced outwardly from the ends of the longitudinal slots and extending from the first longitudinal slot to points beyond the second 55 slot and perpendicularly thereto, the edges of the second longitudinal and transverse slots being provided with graduation lines radiating from said vertex as a center, some of the lines at the ends of the second longitudinal slot being duplicated on the transverse slots to provide continuity of measurements.

55 In testimony whereof I affix my signature,
HARRY A. MUSHAM.
